US0D1040291S

(12) **United States Design Patent** (10) **Patent No.:** **US D1,040,291 S**
(45) **Date of Patent:** **** Aug. 27, 2024**

(54) **WATER FILTER**

(71) Applicant: **CRISOL TECHNOLOGY CO., LTD,**
Guangdong (CN)

(72) Inventor: **Huaping Wu**, Guangdong (CN)

(73) Assignee: **CRISOL TECHNOLOGY CO., LTD,**
Guangdong (CN)

(**) Term: **15 Years**

(21) Appl. No.: **29/827,956**

(22) Filed: **Feb. 23, 2022**

(51) **LOC (14) Cl. 23-01**

(52) **U.S. Cl.** **USPC D23/209**

(58) **Field of Classification Search**

(57) **CLAIM**

The ornamental design for a water filter, as shown and
described.

DESCRIPTION

FIG. 1 is a bottom, rear, left side perspective view of a water filter, showing the claimed design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a bottom, rear, right side perspective view thereof.
The dashed broken lines in the drawing depict portions of
the water filter that form no part of the claimed design.

1 Claim, 7 Drawing Sheets
